(57) **CLAIM**

The ornamental design for a cutting tool for processing a valve sheet, as shown and described.

DESCRIPTION

FIG. 1 is a front view of a cutting tool for processing a valve sheet in accordance with Embodiment 1 of the present design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a first perspective view thereof;

FIG. 8 is a second perspective view thereof;

FIG. 9 is a third perspective view thereof;

FIG. 10 is an enlarged front view of 10 portion of FIG. 5;

FIG. 11 is an enlarged right side view of 10 portion of FIG. 5;

FIG. 12 is an enlarged left side view of 10 portion of FIG. 5;

FIG. 13 is an enlarged top view of 10 portion of FIG. 5;

FIG. 14 is an enlarged bottom view of 10 portion of FIG. 5;

FIG. 15 is an enlarged view of 15 portion of FIG. 7;

FIG. 16 is an enlarged view of 16 portion of FIG. 8;

FIG. 17 is an enlarged view of 17 portion of FIG. 15;

FIG. 18 is a front view of a cutting tool for processing a valve sheet in accordance with Embodiment 2 of the present design;

FIG. 19 is a rear view thereof;

FIG. 20 is a right side view thereof;

FIG. 21 is a left side view thereof;

FIG. 22 is a top view thereof;

FIG. 23 is a bottom view thereof;

(Continued)

FIG. 24 is a first perspective view thereof;
 FIG. 25 is a second perspective view thereof;
 FIG. 26 is a third perspective view thereof;
 FIG. 27 is an enlarged front view of 27 portion of FIG. 22;
 FIG. 28 is an enlarged right side view of 27 portion of FIG. 22;
 FIG. 29 is an enlarged left side view of 27 portion of FIG. 22;
 FIG. 30 is an enlarged top view of 27 portion of FIG. 22;
 FIG. 31 is an enlarged bottom view of 27 portion of FIG. 22;
 FIG. 32 is an enlarged view of 32 portion of FIG. 24;
 FIG. 33 is an enlarged view of 33 portion of FIG. 25; and,
 FIG. 34 is an enlarged view of 34 portion of FIG. 32.
 The broken lines in the drawings depict portions of the cutting tool for processing a valve sheet and environmental subject matter which form no part of the claimed design. The dashed-dot-dashed lines with the reference number in FIGS. 5, 7, 8, 15, 22, 24, 25, and 32 indicate enlarged portions.
